UNITED STATES PATENT OFFICE.

WALTER BAKER, OF FAIRFIELD, IOWA, ASSIGNOR TO SPEEDER MACHINERY CORPORATION, OF FAIRFIELD, IOWA.

TREAD MEMBER FOR TRACTION DEVICES.

Application filed March 24, 1924. Serial No. 701,464.

The object of my invention is to provide a new and improved linked tread member for tractors.

A further object is to provide a tread of light weight and simple, durable and inexpensive construction.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a plan view of the inner faces of three of my improved tread members showing the manner in which they are connected together to form a continuous tread.

Figure 2 is a detail transverse sectional view of same taken on the line 2—2 of Figure 1 showing a position of one of the supporting rollers in section.

Figure 3 is an enlarged detail view showing the manner in which my improved tread is applied to the drive and supporting members of a tractor, only a portion of the said drive and supporting members being illustrated.

My improved tread comprises a tread block 10 which is formed preferably of wood and substantially rectangular and of a length somewhat greater than its width. The inner face of the block 10 is provided with two angle irons 11 having inwardly extending flanges 12 and horizontally extending flanges 13. The upright flanges 12 are spaced apart a slight distance and designed to receive between them a filler bar 14. The angle irons 11 are shorter than the width of the block 10 and secured in position to the inner face of the block by means of bolts 15, the said bolts being designed to extend through plates 16 on the outer face of the tread, as clearly shown in Figure 2. Each of the bolts 15 is provided with a nut 17 which engages the inner surface of the flanges 13.

Secured to the outer face of each of the flanges 12, I have provided a link 18 formed of stock material and each of which is formed exactly alike, and each link being greater in length than the width of the block 10. One end of each link is offset at 19 the offset portions of two links being arranged in a reverse manner so that the ends

19 will rest adjacent to each other, as clearly shown in Figure 1. Each of the ends 19 is provided with a hole 20. The opposite end of each of the links 18 is provided with a hole 21. The links 18, the flanges 12 and the filler bar 14 are all secured together by 55 means of rivets 22. The thickness of the bars 18 is one-half of the combined thickness of the flanges 12 and the filler bar 14.

By this arrangement it will be seen that two tread blocks 10 may be placed side by 65 side and spaced apart a slight distance in such a manner that the two ends 19 of the bars 18 of one block will rest between the opposite ends of the bars 18 of the adjacent block with the holes 20 in alignment with 70 the holes 21. A pin 23 is then placed through the holes 20 and 21, the said pin being of a length slightly greater than the distance between the outer edges of the flanges 13, and provided at each end with suitable 75 openings for receiving cotter pins 24. The pin 23 is formed preferably of stock cold rolled shafting, no machine work being done on it except cutting into the desired length and drilling the holes.

The outer ends of the pins 23 are connected by links 25, each of which has an offset portion 26, and each of which is provided at one end with an opening 27 and the opposite end with an opening 28. The links are 85 placed in position in the manner clearly shown in Figure 1. The said links are of the same width as the links 18 and designed to have their outer edges rest on the outer edges of the flange 13, and the pin 23 being 90 of such length that when the links 25 are in position, their inner faces will rest against the outer face of the nuts 17, as clearly shown in Figure 2. The links are secured in position and held against outward movement by a washer 29 and the pins 24, said links being held against inward movement by the nuts 17 and rollers 24^a which are placed on the pins 23 between the links 18 and 25. The links 25 in turn serve the purpose of locking the said nuts against rotation. The links 18, the flanges 12 and the bar 14 are all of the same width and are designed to form a rim or tread member for supporting rollers 30 of the tractor member 105 31, while the pins 23 and the rollers 24^a serve to form traction members to be engaged by the sprocket teeth 32 of the

sprocket wheel 33. The teeth 32 are arranged in pairs so as to form a notch 34 between which the rollers 24 enter.

By this arrangement it will be seen that 5 I have provided a linked tread for tractors of simple, durable and inexpensive construction which may be formed of stock material and which requires a minimum amount of machine work, the angle bars simply being 10 cut into the proper length and the holes for the bolts and rivets being punched or drilled. The bars 18 are also formed of stock material, and the two are alike, requiring but one set of dies for forming. The pin 23, as 15 before stated, is simply a piece of cold rolled shafting with two holes drilled for the cotter pins.

The tread member is one which is easy and quick to assemble or take apart. If it 20 is desired to replace a broken block, the operator first removes two of the pins by pulling the adjacent cotter pins and then removing the nuts 17, after which the block is free to drop from the link portion of the chain. 25 A new one can easily be inserted by a reverse operation, the entire change requiring but a few minutes. The inner edges of the bars 18 form a track for supporting the rollers 30, as before stated.

30 I claim as my invention:

1. A tread member comprising a tread block, a pair of angle irons having horizontal and vertical flanges arranged with their vertical flanges parallel and spaced apart, a 35 filler bar, a pair of links, means for securing said links, said vertically extending flanges and said bar together, and means for detachably securing the horizontal flanges of said angles to said blocks.

40 2. A tread member comprising a tread block, links extending centrally and transversely across said block, means for detachably securing said links to said block, the inner edges of said links serving as a track, 45 the ends of said links being provided with transverse openings, a pin for each set of corresponding openings, a link for each end of said pin, and means for detachably securing said links in position parallel and spaced 50 apart from the inner links.

3. A tread member comprising a tread block, a link extending centrally and transversely across the inner surface of said block, having outwardly extending flanges 55 to rest thereon, bolts extending inwardly

through said block and through said flanges, a nut for the inner end of each of said bolts, a pin extending transversely through each end of said links, an outer link for each end of said pin, the links of one block being designed to pivotally receive the pin of an adjacent block, the outer links being designed to rest against the outer one of the faces of said nuts to prevent said nuts from loosening, and means for detachably securing the links in position on said pins to hold the links against outward movement.

4. A tread member comprising a rectangular tread block, a pair of angle irons shorter than the width of said block placed transversely and centrally on the inner surface of said block, said angle bars being provided with horizontal and vertical flanges with the vertical flanges parallel and slightly spaced apart, a filler bar between said flanges, a link adjacent to the outer face of each of said vertical flanges, and rivets for rigidly securing said links, said vertical flanges and said filler bar together, the ends of said links extending beyond the ends of said angle 80 irons and the edges of said block, the two adjacent ends of said links being bent inwardly to engage each other and provided with transverse openings, the opposite ends of said links also being provided with openings, the thickness of said links being one-half of the combined thickness of said vertical flanges and said filler bar, a pin extending through said transverse openings of uniform diameter throughout its length 90 having at each end an opening to receive a cotter pin, a pair of plates outwardly of said tread block, bolts extending inwardly through said plates and through said horizontal flanges, a nut for the inner end of each of said bolts, an outside link for the end of each of said pins, one end of said link being offset, said links being of the same length as the first said links and with openings in alignment with the openings of the first said links designed to receive said pins, the inner faces of said outside links resting adjacent to one of the outer faces of said nuts to hold the said link spaced apart from the first said link, a cotter pin for the holes of said pin to prevent the said outside links from moving outwardly, the inner edges of said central links being designed to form a track.

WALTER BAKER.
